Edwin North
INVENTOR.

BY Clarence E. Thruedy

HIS ATTORNEY.

UNITED STATES PATENT OFFICE

2,059,479

LATCHING DEVICE

Edwin North, Rockford, Ill., assignor to National Lock Co., Rockford, Ill., a corporation of Illinois

Application February 20, 1935, Serial No. 7,387

1 Claim. (Cl. 292—127)

This invention relates to a latching device.

It is an object of this invention to provide an improved latching device which is relatively simple and inexpensive in construction and efficient in use.

Another object of this invention is to provide an improved door latching device.

A further object of the invention is to provide an improved device for latching gas oven doors or other stove oven doors, and which is so constructed that it is responsive to, and automatically becomes unlatched by, the gas pressure inside the oven if the said gas pressure, for any reason, rises above a predetermined safety point.

Other objects will appear hereinafter.

The invention consists in the novel combination and arrangement of parts to be hereinafter described and claimed.

The invention will best be understood by reference to the accompanying drawing, showing the preferred form of construction and in which:

Fig. 1 is a fragmentary perspective view of a gas stove showing a preferred form of the new latching device associated therewith;

Fig. 2 is a vertical sectional view of the new latching device, on line 2—2 in Fig. 1, showing the parts in latched position;

Fig. 3 is a sectional view similar to Fig. 2 but showing the parts in unlatched position;

Fig. 4 is a bottom plan view, on line 4—4 in Fig. 2;

Fig. 5 is a side view of the latching device on line 5—5 of Fig. 4;

Fig. 6 is an end elevational view, partly in section, on line 6—6 in Fig. 5.

A preferred form of the new latching device is shown in the drawing, is therein generally indicated at 10, and is shown in conjunction with a gas stove 11 which includes an oven 12 provided with a door 13.

The new latching device 10 includes a support or flange 14 which projects laterally or forwardly from the oven door 13, this flange 13 having a depending skirt 34 (Fig. 2). Slidably projected through an opening formed in the skirt 34 of the flange 14 is a plunger or actuating member 16, which has a handle portion 17. The inner end portion 18 of this plunger or actuating member 16 is slidably projected into an opening 19 which is formed in a plate 31 which is attached to the oven door 13 at the front thereof, and the inner end portion 18 of the plunger or actuating member 16 is adapted to engage against a nose or cam portion 32 of a latch-operating member 20 which is pivotally mounted upon a shaft or pintle 21, in a

pocket or recess 22 which is provided in the oven door 13. Provided on the plunger or actuating member 16 is an annular flange 33.

The latch-operating member 20 is pivotally connected, as at 23, to the lower end portion of spaced links 24 and these links 24 are pivotally connected at their upper ends, as at 25, to a male latch element or bolt 26; the male latch element or bolt 26 being pivotally mounted at one end, as at 27, in the pocket 22, on the inner side of the front face of the oven door 13.

Formed in the stationary wall 35 of the oven door 13 is a recess or keeper or female latch element 28 and the male latch element or bolt 26 has a latching head or end portion 29 which is engageable in the recess or keeper 28 and is normally urged into latching engagement with the female latch element or recess or keeper 28 by the action of a spring 30 which is arranged upon the shaft 21.

Operation

The spring 31 normally acts upon the member 20 to urge the latter in a counterclockwise direction, as seen in Figs. 2 and 3, thereby urging the nose or cam portion 32 of the latch-operating member 20 into engagement with the inner end portion of the plunger 16, so as to force the latter outwardly relative to the oven door, (right to left, Figs. 2 and 3), the outward movement of the plunger 16 being limited by the engagement of the flange 33 formed thereon with the depending skirt 34 of the flange 14.

This action of the spring 30 in urging the member 20 (counterclockwise, Figs. 2 and 3) into engagement with the inner end of the plunger 16 also acts, through the links 24, to urge the male latch element or bolt 26 in a counterclockwise direction, as seen in Figs. 2 and 3, thereby forcing the latching head 29 on the male latch element or bolt 26 into latching engagement with the recessed portion or female latch element or keeper 28 which is formed in the wall 35 of the oven door 13.

In order to unlatch the male latch element 45 or bolt 26 from latching engagement with the female latch element or recess or keeper 28, so as to open the oven door 13, the operator pushes inwardly (left to right, Figs. 2 and 3) upon the plunger or actuating member 16, whereupon the inner end portion 18 of the plunger 16 engages the cam portion or nose 32 of the latch-operating member 20 and thereby pivots the latter (clockwise, Figs. 2 and 3, from the position of Fig. 2 into the position of Fig. 3). This motion of the latch- 55

operating member 20 acts through the links 24 to pivot the male latch element or bolt 26 (clockwise, Figs. 2 and 3, from the position of Fig. 2 into the position of Fig. 3), thereby withdrawing 5 the head portion 29 of the male latch element or bolt 26 out of latching engagement with the recess or female latch element or keeper 28 so that the oven door 13 may be opened.

The latching engagement of the head portion 10 29 of the male latch element or bolt 26 with the keeper 28 prevents the oven door from being opened by normal or safe gas pressures in the oven 12 but if, for any reason, the gas pressure in the oven 12 should rise above a predetermined 15 pressure or safety point such as, for example, 30 pounds per square inch, the outward pressure or force exerted upon the oven door 13 (right to left Figs. 2 and 3) will act upon the latch member or bolt 26—29 to pivot the same (clockwise Figs. 2 and 3) so that the head 29 of the male latch element or bolt 26 will pass the retaining wall or keeper 36, thereby permitting the oven door 13 to pivot (counter-clockwise, Figs. 2 and 3) into open position, and thus preventing the gas 20 pressure in the oven from rising to a point where danger of explosion might result; it being noted that the retaining wall or keeper 36 is rounded to permit the head 29 of the male latch element or bolt 26 to move around or past the same gradually under the action of the force exerted thereon by the pressure of the gas in the 25 oven.

While I have illustrated and described the preferred form of construction for carrying my

invention into effect, this is capable of variation and modification, without departing from the spirit of the invention. I, therefore, do not wish to be limited to the precise details of construction set forth, but desire to avail myself of such 5 variations and modifications as come within the scope of the appended claim.

Having thus described my invention, what I claim as new and desire to protect by Letters Patent is: 10

A latch structure for a gas stove door comprising a recessed keeper plate associated with a wall portion of a gas stove with which the door is associated, a latch member pivotally supported by the door and including a latch head engageable in the recess and adapted to be disengaged therefrom when a predetermined pressure is applied to the door in one direction, an operated member pivotally carried by the door and including a cam head, a link member providing a connection between the latch member and the operated member, said link member having connection with the operating member at a point substantially spaced from the cam head, a plunger exterior of the door and movable into engagement with 20 the cam head for pivoting the operated member in a direction to cause the link member to pivot the latch member from latched engagement with the recess of the keeper plate, and spring means for pivoting the operated member in an opposite 25 direction to dispose the latch member in latched engagement with respect to the recess of said keeper plate, substantially as described.

EDWIN NORTH.
